LAMP SOCKET

Filed May 1, 1926

Inventor:
Percy S. Bailey,

by Alexander S. Smith,
His Attorney

UNITED STATES PATENT OFFICE

PERCY S. BAILEY, OF MARBLEHEAD, MASSACHUSETTS, ASSIGNOR TO GENERAL ELECTRIC COMPANY, A CORPORATION OF NEW YORK

LAMP SOCKET

Application filed May 1, 1926. Serial No. 106,125.

My invention relates to lamp sockets. More particularly it relates to lamp sockets adapted for use in connection with high current lamps such as high current incandescent lamps which are adapted for use in connection with motion picture studios or for illuminating aviation fields. Lamps of this character may range above 10 kilowatts in power consumption.

It is an object of my invention to provide a socket which is especially adapted for supporting high current lamps of the above character.

My invention will be more readily understood by reference to the accompanying drawing, specification and claims.

Referring to the drawing, Fig. 1 shows the socket of my invention in perspective; Fig. 2 shows the socket in side elevation with one size of lamp in position; Figs. 3 and 4 show details of the socket; Fig. 5 shows the base of one of the higher power lamps, such as for a 30 kilowatt lamp.

Referring more in detail to the drawing, and in particular to Fig. 1, the socket is provided with a base 2 preferably threaded internally, which base is adapted to be screwed to any suitable support such as an iron pipe 2', see Fig. 2. The base is provided with an upward projecting flange 3 to which are clamped the socket terminals 4 and 5, which are suitably insulated from each other and from the flange. Above the socket terminals 4 and 5 there is mounted a plate 6 having a central opening (see Fig. 3) within which a removable fitting element 7 (see Fig. 4) is secured. This fitting is provided with an opening 11 through which the base 12 of one of the smaller size of lamps 13 projects (see Fig. 2).

When it is desired to operate one of the higher power lamps 13' the fitting 7 is removed and the base 12' is inserted in the opening in the plate 6. The base of the lamp, whether of a large or of a small size, is provided with terminal stems to fit the openings in the terminals 4 and 5 shown in Fig. 1.

For example, Fig. 5 in which a large size lamp is represented, shows such stems 8 and 9, which stems constitute the terminals of

the filaments of the lamp. In Fig. 2 the small size lamp is shown with similar stems in the socket terminals. These socket terminals, as shown in Fig. 1, are provided with screws 10 and 10' for clamping the prongs and for holding the lamp in place. The lamp, whether large or small, may be adjusted longitudinally of the socket before the screws are tightened, as shown for example in Fig. 2. When the small lamp is used the removable element 7 acts as a guide for the base element 12 of the lamp and when the large size lamp is used the plate 6 acts as a guide for the base element 12'. The base element 12' corresponds to the base element 12, but the former is much shorter, terminating, when in position, considerably below the guide plate 6, Fig. 1. As shown, the base element 12' is located above the base element 12 and is adapted to rest snugly in the opening of the guide plate 6.

As indicated in Fig. 2, the device as a whole may be mounted on the end of a supporting pipe 2' to which latter the device may be screwed. When thus mounted connections from a suitable current source may be made with the terminals 4 and 5 by means of wires extending through the pipe and through the hollow base 2 of the device, the ends of the wires being secured to the terminals by means of screws 14 and 15.

It will be seen, therefore, that I provide an improved socket especially adapted for use in connection with high power incandescent lamps, which is constructed so that either large or small size lamps may be used. For the smaller lamp the fitting 7 serves to steady the lamp. For the larger size lamps the plate 6 serves to steady the lamp.

While I have elected to describe my invention in connection with a specific embodiment of socket, I do not wish to be so limited, inasmuch as in view of the disclosure variations may be made without departing from the spirit of the invention or from the scope of the claims contained herein.

What I claim as new and desire to secure by Letters Patent of the United States, is:

1. An electric lamp socket adapted to receive a lamp, the latter having a base and

- terminal stems projecting therefrom, said socket comprising a hollow base through which cable connections may be made to the socket, a flange projecting from the base of the socket, parallel to the longitudinal axis of the socket, a terminal for each stem secured to said flange, said terminals having their longitudinal axes extending parallel to the said axis of the socket, said terminals being insulated from each other and each being provided with an opening for receiving its corresponding stem, a guide plate for said lamp base located over said terminals, said plate having an opening through which the lamp base and its stems may be inserted to engage said terminals, the opening of the hollow base and the said opening in said plate being located in juxtaposition to said terminals, the latter being interposed between the guide plate and the hollow base. 75
2. An electric lamp socket adapted to receive a lamp, the latter having a base and terminal stems projecting therefrom, a flange projecting from the base of said socket and extending parallel to the longitudinal axis of the socket, a terminal for each stem secured to said flange, said terminals having their longitudinal axes extending parallel to the said axis of the socket, said terminals being insulated from each other and each terminal being provided with means whereby the corresponding stem may be secured thereto, a guide plate located over said terminals with an opening in juxtaposition to said terminals, through which opening the lamp base and its stems may be inserted to engage said terminals, said terminals being located between said plate and base of the socket. 80
3. An electric lamp socket adapted to receive a lamp, the latter having a base and terminal stems projecting therefrom, said socket comprising a hollow base through which cable connections may be made to the socket, a flange projecting from the base of the socket, parallel to the longitudinal axis of the socket, a terminal for each stem secured to said flange, said terminals having their longitudinal axes extending parallel to the said axis of the socket, said terminals being insulated from each other and each being provided with an opening for receiving its corresponding stem, a guide plate for said lamp base located over said terminals, said plate having an opening through which the lamp base and its stems may be inserted to engage said terminals, the opening of the hollow base and the said opening in said plate being located in juxtaposition to said terminals, the latter being interposed between the guide plate and the hollow base, said guide plate being provided with a ring nested in said opening of said guide plate, said ring having a smaller opening adapted to receive a similar lamp having a smaller base whereby 85
